UNITED STATES PATENT OFFICE.

FREDERIC S. GABLE, OF GLEN ROCK, PENNSYLVANIA.

MECHANISM FOR CONVERTING MOTION.

SPECIFICATION forming part of Letters Patent No. 290,566, dated December 18, 1883.

Application filed October 26, 1883. (No model.)

To all whom it may concern:

Be it known that I, FREDERIC S. GABLE, a citizen of the United States, residing at Glen Rock, in the county of York and State of Pennsylvania, have invented a new and useful 5 Mechanism for Converting Motion, of which the following is a specification, reference being had to the accompanying drawings.

This invention relates to mechanism for converting rotary into reciprocating motion; and it has for its object to produce a mechanism particularly adapted to operate the cutter-bars in harvesters, which shall possess superior advantages in point of simplicity, durability, and 15 general efficiency.

To this end it consists in certain improvements in the construction of the same, which will be hereinafter fully described, and particularly pointed out in the claims.

20 In the drawings hereto annexed, Figure 1 is a side view. Fig. 2 is a plan view. Fig. 3 is a longitudinal vertical sectional view on the line *xx* in Fig. 2, and Fig. 4 is a transverse vertical sectional view on the line *yy* in Fig. 2.

25 The same letters refer to the same parts in all the figures.

A in the drawings designates a suitable frame, which may be the frame of a harvester, and which is provided with bearings for the 30 revolving axle B, carrying the transporting and operating wheels C C. It will of course be understood that this part of the invention may be varied, and that a stationary frame may be used having a revolving shaft, to which 35 motion may be imparted in any suitable manner, my invention for converting motion being applicable to all kinds of machinery, stationary or locomotive, where such conversion of motion is desired. The shaft A carries a cog- 40 wheel or spur-wheel, D, engaging an interiorly-toothed wheel or band, E, which works eccentrically around the said spur-wheel D. Said band has a forwardly-extending rod or arm, F, provided with a box or bearing, G, in 45 which is journaled a crank, H, formed upon a shaft, I, bearings for which, J J, are provided upon the frame A, in front of the shaft or axle. The box G has a cap-plate, K, serving to hold the crank in its bearing. Shaft I carries a fly 50 or balance wheel, L. The function of the crank-shaft I is to hold the band E in gear with the spur-wheel D and to prevent dis-

placement of the said band, and the fly-wheel L serves to overcome the dead-centers.

Pivoted horizontally upon the front part of 55 the frame A is a bell-crank lever, M, to one end of which the front end of the rod or arm F is connected by a ball-and-socket joint, N. The other arm of the said bell-crank lever is to be connected by a pitman with the machinery to be driven.

From the foregoing description, taken in connection with the drawings hereto annexed, the operation and advantages of this invention will be readily understood. As the shaft 65 or axle revolves, it imparts, through the band E, a reciprocating motion to the arm F, and from the latter, through the bell-crank lever, to the machinery to be driven. The speed may be regulated by the relative sizes of the 70 spur-wheel D and band E.

The construction is simple and not liable to get out of order, and the operation is effective. Having thus fully described my invention, I claim and desire to secure by Letters Patent 75 of the United States—

1. In mechanism for converting motion, the combination, with a revolving shaft or axle carrying a spur-wheel, of an interiorly-toothed wheel engaging the said spur-wheel eccentrically, and having an extending rod or arm, to which an oscillating and reciprocating motion is thus imparted, substantially as set forth. 80

2. In mechanism for converting motion, the combination of a revolving shaft or axle carrying a spur-wheel, an interiorly-toothed wheel engaging the said spur-wheel eccentrically, and having an extending rod or arm provided with a box or bearing, a shaft journaled in front of the axle and having a crank journaled in the 90 said bearing, and a balance-wheel mounted upon the said shaft, substantially as set forth. 85

3. In mechanism for converting motion, the combination of a revolving shaft or axle carrying a spur-wheel, an interiorly-toothed wheel 95 engaging the said spur-wheel, and having a forwardly-extending arm, a crank-shaft the crank of which is journaled in a box or bearing in the said arm, and a bell-crank lever, one arm of which is connected with the front 100 end of said arm by a ball-and-socket joint, substantially as set forth.

4. The herein-described device for converting motion, the same comprising a frame, an

axle journaled transversely in the same, and having a pair of transporting-wheels and a spur-wheel fixedly secured thereon, an interiorly-toothed wheel engaging the said spur-wheel, and having a forwardly-extending arm provided with a box or bearing, a shaft mounted transversely in the frame, in front of the axle, and having a crank journaled in the said box or bearing, a balance-wheel mounted upon the said shaft, and a bell-crank lever pivoted horizontally upon the front part of the frame, and

having one arm connected by a ball-and-socket joint with the front end of the arm extending from the interiorly-toothed band, substantially as set forth.

15

In testimony that I claim the foregoing as my own I have hereto affixed my signature in presence of two witnesses.

FREDERIC S. GABLE.
